UNITED STATES PATENT OFFICE.

DAVID R. NICHOLS, OF BROCKVILLE, PROVINCE OF ONTARIO, CANADA.

CARPET-SWEEPER.

SPECIFICATION forming part of Letters Patent No. 288,590, dated November 13, 1883.

Application filed October 23, 1882. (Model.)

To all whom it may concern:

Be it known that I, DAVID R. NICHOLS, a citizen of the United States, and a resident of Brockville, in the county of Leeds and Province of Ontario, Canada, have invented a new and valuable Improvement in Carpet-Sweepers; and I do hereby declare that the following is a full, clear, and exact description of the construction and operation of the same, reference 5 being had to the annexed drawings, making a part of this specification, and to the letters and figures of reference marked thereon.

Figure 1 of the drawings is a bottom view of my sweeper. Fig. 2 is a top or plan view 15 of the same. Figs. 3 and 4 are cross-sectional views, and Figs. 5 and 6 are detail views.

This invention has relation to carpet-sweepers; and it consists in the construction and novel arrangement of parts, as will be hereinafter fully described, and particularly pointed out in the claim appended.

In the accompanying drawings, the letter A designates the arched top of the case, consisting of the curved sheet-metal pieces B, the 25 grooved edge strips, C, and the grooved top piece, D, into which the edges of the pieces B are let, and the end castings, E, which are secured to the ends of the edge strips and top strips. The castings at the end of this case 30 give it strength and the proper weight to keep the machine down to its work. One of the end castings is formed with a center bearing, *a*, opening from the bottom, and designed to receive the movable journal-seat *b*, which supports the journal at the head of the brush-shaft F. Near this end casting is arranged a 35 partition, G, which is fastened to the parts D and C of the case, and serves to separate the dust-chamber from the compartment in which 40 the wheels work. The partition G is made with a central notch opening from its bottom, and designed to provide for the passage of the brush-shaft, the main portion of which lies in the dust-chamber, while its head and collar bearing, *c*, are in the wheel-compartment.

H H represent the wheels, which are provided with rubber tires, and have central hubs, which are seated on spindles *d*, which project from plate-arms *e*, which are pivoted to 50 the partition G, the pivots passing through horizontal slots *g* in said plates, which are provided to allow a movement of the plate-

arms, spindles, and wheels toward the collar on the brush-shaft, which is engaged by the tires of said wheels and operated thereby 55 when the machine is in motion over a carpet. The arms *e* are drawn toward each other and pressed toward the intermediate brush-shaft by a spring or springs, *h*, which exert not only an inward pressure but also a downward 60 pressure on the wheels.

The journal at the tail end of the brush-shaft moves in a bearing, *b'*, on the end of a spring-arm, I, which is fastened at its other end and secured to the end of the case. This 65 flexible bearing allows the brush to move easily over inequalities of the carpet and adapt itself to the surface presented.

The bottom K of the case consists of end arms, L L', which are hinged to one edge of 70 the case, and are connected longitudinally by the dirt-trays N N, between which is the longitudinal opening through which the brush operates. Each dirt-tray consists of a sheet-metal plate having its edges turned upward 75 to form an outer wall, *k*, and an inner wall, *k'*, the latter being inclined over the tray, in order to hold the dust and débris more securely, as indicated in the drawings. The edge of the bottom is provided with a spring-catch, *l*. 80 The arm L', which is at the end of the case opposite that having the operating-wheels, is provided with a rounded shoe or runner-base, *m*, on which this end of the case moves.

The top of the case is provided with ears, 85 V, each of which is formed with a bearing-recess, *v*, for the journal *z* of the bail Z, to which the handle of the machine is secured. The bearing-recess of one of the ears is made in enlarged form, or elliptical, and is provided 90 with a notch, *n*, in its bottom, to receive a stop projection, *s*, on the journal of the corresponding end of the bail. When the handle is in the upright position, the stop will automatically engage the notch *n* and hold the handle 95 vertical. In order to disengage the handle, it is only necessary to give it a slight lateral movement, which will raise the stop out of the notch and allow the journal to turn in its vertical.

A handle for a carpet-sweeper, bearing concentric with the shaft, and provided with a latch which will engage with either of several notches on a disk fixed to the shaft, so that

the handle may be set upright or secured in any desired position, has been known prior to my invention, and vertical slide-bearings for one or both ends of the brush-roller are old, 5 and neither of these constructions is claimed, broadly, herein.

Having described this invention, what I claim, and desire to secure by Letters Patent, is—

- 10 A carpet-sweeper having an automatic stop-fastening for its pivoted handle, consisting of the ears V , secured to the top of the case, and provided with the recesses v for the journal z of

the bail Z , to which the handle of the machine is secured, one of said bearings being made 15 in enlarged form, and provided with a notch, n , to receive a stop projection, s , on the journal of the corresponding end of the bail, substantially as specified.

In testimony that I claim the above I have 20 hereunto subscribed my name in the presence of two witnesses.

DAVID RICHARDSON NICHOLS.
